VARIABLE INDUCTANCE DEVICE

Alfred Schöne, Berlin-Tempelhof, and Friedrich Troeltsch, Berlin-Siemensstadt, Germany, assignors to Siemens & Halske, Aktiengesellschaft, Siemensstadt, near Berlin, Germany, a corporation of Germany

Application May 9, 1936, Serial No. 78,760
In Germany May 27, 1935

1 Claim. (Cl. 171—119)

In the use of air-cored tuning and coupling coils employed, e. g., in broadcast apparatus, it is imperative to make the shielding means (can) considerably larger than the radio frequency coil which is to be screened, in order that the losses caused by stray flux in the shielding container may be minimized.

In the case of coils to be used in radio frequency work having a magnetizable core of the 10 molded or dust material type which are preferably used in the winding because of their low losses, the stray field in most forms of construction is placed at close proximity around the coil so that there is a chance for placing the shielding 15 cans quite snugly about the coil without any incidental growth of losses having to be feared.

Radio frequency coils comprising a magnetizable core, however, involve the disadvantage that their self-capacitance grows very considerably as 20 a result of the introduction of the core. Moreover, difficulties arise in connection with the arrangement of a winding which must be wrapped directly upon the core rather than being manufactured in a separate working stage and 25 being then only placed upon the core.

The present invention indicates ways and means for a more suitable construction of radio frequency coils having a magnetizable core which combines the advantages residing in a low stray 30 field and ready balance or adjustment with ease of assembly and essential reduction of inherent or self-capacitance. According to this invention, in radio frequency coils having a core of magnetizable material resembling molded or dust cores, the core is disposed adjustably inside the 35 coil winding, the latter being, in turn, surrounded about its outer periphery by a shell of like material as the core. The said shell, as it were, contributes to a concentration of the stray field, with 40 the latter's path being completed snugly about the coil by the aid of the shell. It goes without saying that the shell causes also an increase in inductance so that a given value is obtainable with a smaller number of turns than is true, for 45 instance, of air-core coils. The core introducible in the interior of the coil acts in a similar manner; this core, as will be remembered is adapted to fix and secure a certain inductance value.

The present invention is illustrated in the annexed drawing containing Figs. 1 to 3 showing a number of exemplified embodiments, the figures being partly in section.

In Fig. 1, 1 denotes the coil winding which is wrapped upon an insulating tube 2. The latter 55 may serve as a form for the coil winding 1, or else

the winding is made separately and is later shifted onto the insulation tube 2. Inside the insulation tube 2 is shiftably disposed a preferably cylindrical core 3 made from magnetizable substance, said core being of rod-shape and being 5 employed for the purpose of balancing or adjusting a definite inductance value. For setting to a certain depth of introduction in reference to coil 1 recourse may be had to a screw-thread or worm 4 which may be journaled, for example, in 10 the wall 5 of a shield or can. Upon its outer circumference the coil winding 1 is surrounded by a shell-shaped core 6 consisting of magnetizable material which shell, as pointed out before, serves to prevent the spreading of the stray field beyond 15 the space remoter from the circumference of the coil. As can be seen from the drawing, the said shell has a flange-like extension projection inwardly as indicated at 7 with the result that the cross-section of the shell is L-shaped. By the 20 said flange 7 is avoided any chance of lateral shifting of the coil inside the shell after assembly and more particularly after the adjustment of a definite inductance value. However, this form of construction offers the further merit that the 25 coil field is able to extend somewhat farther towards the open end of the shell in the direction of the coil axis than towards other sides of the circumambient space so that other coils may there be coupled, say, a coil of identical kind being 30 the image of the coil shown on the insulation tube 2.

For coarse adjustment desired portions may be removed by grinding or in the lathe from the open end of the shell core which projects slightly 35 beyond the coil winding.

In the exemplified embodiment shown in Fig. 2 a coil winding 1 having no supporting means or form is used. On the other hand, the inside diameter of the winding is chosen sufficiently 40 large in order that the balancing or adjusting core 3 made of magnetizable material may be passed through with sufficient clearance or play. Also in this embodiment the adjusting or balancing core is furnished with a screw-thread or 45 worm part 4 which is journaled in the central portion 8 of a clip piece 9 made of low-loss insulation material, such as Trolitual. The said clip or bow is fastened by screwing on the shell core 6 surrounding the coil winding 1 externally in 50 the same manner as shown in Fig. 1.

This embodiment has the advantage that, if desired, it could be used without the provision of any distinct shielding means or can, inasmuch as the supporting or holder means for the bal- 55

ancing or adjusting core may be provided directly on the coil arrangement. The clip-shaped supporting is chosen for the reason that a maximum of freedom or mobility may be insured for the balancing core in the adjustment of the inductance. It will be understood that the construction could be also chosen in such a way that on the outer shell-shaped part a plate of insulation material such as Trolitual is screwed fast and which carries in the middle a screw-threaded balancing or adjusting core. This means a reduction in the cost of manufacture and the supporting of the adjuster cores.

Exemplified embodiments Figs. 1 and 2 illustrating the invention make it clear that all parts of the new coil arrangement, more particularly the winding, are made in separate working or production stages and that it is only then that they are assembled. The drawback inhering in the fact that in the arrangement of the prior art the winding may be fitted upon the core only by direct wrapping thereon is obviated in the new form of construction here disclosed. Moreover, on account of the fact that unlike the embodiments known in the prior art, the coil winding is not extensively surrounded by the magnetizable core, the self-capacitance is made very small. Fig. 3 shows a coupling device comprising the use of the new type of radio frequency coil here disclosed.

Inside a pot-shaped or can container 10 are disposed coaxially to each other two of the new coil arrangements 10 and 11. The open ends of the shell-shaped core part are turned toward

each other so that a coupling relation will be insured by the aid of the fields extending in these directions, it being understood that looser or stronger coupling is established according to the point of approach of the parts. The coil units are secured on can 10 by the aid of holding arms or bracket pieces 13 which are made integral with an annular disc 16 of low-loss material such as Trolitual fastened on the shell core. The fastening screws 14 are preferably passed through oblong slots 15, mutual adjustment in position of the coil units 11 and 12 being feasible by loosening the said screws.

I claim:

A high frequency electrical coupling device comprising a pair of coupled inductance coils, each of said coils being mounted within an open shell made of compressed powdered magnetic material, said inductance coil shells being mounted within a shielding can and so that the open faces of the shells face each other, means adjustable from the outside of said can for displacing at least one of said shells and its associated coil as a unit with respect to the other shell and associated coil to provide variable coupling between the coils, each of said coils being provided with an individual movable core made up of substantially similar material as said shells and individual means mounted on each of said shells for displacing each of said cores with respect to its associated coil to provide each coil with independent means for varying the inductance value thereof.

ALFRED SCHÖNE.
